UNITED STATES PATENT OFFICE.

HAROLD S. ASHENHURST, OF CHICAGO, ILLINOIS, ASSIGNEE, BY MESNE ASSIGNMENTS, TO INSULEX CORPORATION, OF CHICAGO, ILLINOIS, A CORPORATION OF DELAWARE.

MONOLITHIC WALL AND METHOD OF BUILDING THE SAME.

Application filed February 16, 1925. Serial No. 9,639.

My invention relates to walls for buildings, composed of cellular insulating material such as described in my prior patent, Reissue No. 15,952, of November 25, 1924.

5 This material is formed first in plastic condition by the addition of water to a prepared powder, the same being adapted to expand very materially and then to set and harden in highly cellular form.

10 It is one of the objects of my invention to build vertical walls by providing suitable encasing elements for defining the thickness of a wall and pouring the cellular material while in plastic condition into the form

15 where it expands and sets. It is another object of my invention to provide a wall of this type in which there are no parts extending through the wall from one face to the other of a character adapted to conduct heat

20 or sound through the wall. To this end, it is one of my objects to provide a construction in which the supporting elements of the wall are completely embedded in the body of insulating material.

25 It is another object of my invention to provide a new and improved arrangement of body and supporting means whereby the upper portion of the wall can be built to advantage at the point adjacent to the ceiling of the room. To this end, it is one of

30 the objects of my invention to provide a construction of such arrangement that the lower portion may be built advantageously in integral form, with the upper portion capable of being completed by the addition of separately formed blocks.

35 It is another object of my invention to improve walls in sundry details hereinafter pointed out. The preferred means by which I have accomplished my several objects are illustrated in the drawing and are hereinafter specifically described. That which I believe to be new and desire to cover by this application is set forth in the claims.

40 In the drawings,—

45 Fig. 1 is a face view of fragmentary portions of a wall embodying my invention, showing the ceiling and the floor of the room in section; and

50 Fig. 2 is a sectional view taken substantially at line 2—2 of Fig. 1.

Referring to the drawing, 10 indicates studs in the form of tubes or bars of metal extending in substantially vertical position

between a floor 11 and a ceiling 12, such 55 studs being arranged in suitable spaced relation to each other. About the studs or supports 10, I have provided a wall body 13 formed integrally from the floor 11 to a point close to the ceiling 12. This body 13 is preferably formed by the use of a plastic mass poured into position between forms of any suitable type held in spaced position with respect to each other at opposite sides of the studs 10 and preferably held in spaced 60 position with respect to said studs so that the face of the wall shall be continuous past the studs. By employing a form of plastic material such as that disclosed by my prior patent above referred to, I have insured 70 that the body 13 shall be of cellular formation throughout, whereby it may have a high insulating value.

When the body 13 has reached a point 75 adjacent to the ceiling 12 such that it is difficult to pour the plastic material into position between the forms, the integral casting operation is preferably discontinued, the space between the upper edge of the body portion 13 and the ceiling being filled in 80 with blocks 14 formed separately by casting operations conducted preferably near at hand so as to enable the blocks 14 to be removed from the mold and placed in position in the wall while still moist. By this 85 procedure, the blocks are capable of being fitted snugly into position between and about the studs 10 and in tight joint relationship with the top edge of the integral portion 13 of the wall.

90 By my arrangement, a very effective wall is provided, from the standpoint of insulation, the extreme cellularity of the material forming the body 13 and the blocks 14 rendering the material very effective for insulating both heat and sound. By arranging the cellular material so as to extend past both faces of the studs 10, the insulation is made much more efficient as compared with constructions in which the studs extend from 95 one face of the wall to the other face. At the same time, the studs 10 are able to reinforce and support the cellular material effectively in position so as to secure the desired strength of the wall structure. By using 100 care in the preparation of the forms and in the pouring of the wall material, as well as in the arrangement of the blocks 14 at the

upper portion of the wall, smooth face portions may be produced such as to require no finishing coat of plaster.

While I prefer to employ the form of cellular material as described and claimed in my said prior reissued patent as above suggested, I do not wish to be limited in this respect, except as certain limitations may be specifically claimed. I have obtained good results by the use of materials mixed on the job with sufficient water to form a free-flowing paste and poured into place in the form, such materials consisting of ingredients mixed as follows,—100 pounds of calcined gypsum, 2 ounces of commercial retarder, $3\frac{3}{4}$ pounds of a suitable carbonate such as calcium carbonate, and 8 pounds of aluminum sulphate containing its water of crystallization, all of such ingredients being finely ground and thoroughly mixed in a dry state.

I also do not wish to be limited with respect to any of the details of the construction, except so far as the same may be specifically claimed, inasmuch as it is evident that changes may well be made from the form shown without departing from the spirit of my invention.

I claim:

1. A wall comprising a body of cellular material of high insulating value and composed mainly of gypsum, of integral construction at its lower portion and built up of separate blocks at its upper portion.

2. A wall comprising in combination a body of cellular material of high insulating value and composed mainly of gypsum, of integral construction at its lower portion and built up of separate blocks at its upper portion, and a plurality of supporting members secured in said body at intervals therealong serving to hold the body rigidly in position with respect thereto.

3. A wall section comprising in combination a plurality of studs extending between a floor and a ceiling and permanently secured in position in spaced relation to each other, and a body of cellular insulating material filling the spaces between the studs and completely surrounding the studs, serving as the body of the wall and being self-supporting vertically from the bottom to the top of the wall section, the major portion at least of the body being of continuous integral formation.

Signed at Chicago, Illinois, this 13th day of February, 1925.

HAROLD S. ASHENHURST.
